UNITED STATES PATENT OFFICE

FRANÇOIS BAVEREY, OF OULLINS, FRANCE, ASSIGNEE TO SOCIETE DU CARBUREATEUR
ZÉNITH, OF LYON, FRANCE, A CORPORATION OF FRANCE.

CARBURETEER.

1,259,072.

Specification of Letters Patent. Patented Mar. 12, 1918.

Application filed February 7, 1914. Serial No. 817,276.

To all whom it may concern:

Be it known that I, FRANÇOIS BAVEREY, a citizen of the French Republic, residing at Oullins, in France, have invented certain new and useful Improvements in Carbureters for Explosion-motors, of which the following is a specification.

This invention relates to an improved carbureter for explosion motors of the automatic suction type, as distinguished from the mechanical control type. It also relates particularly to that type of suction carbureter wherein two sources of liquid fuel supply are used, one subject to the suction and 10 the other delivering an approximately constant amount of liquid fuel per unit of time; such as set forth in my Patent No. 907,953, dated December 29, 1908.

The invention consists broadly in uniting 20 the liquid fuel supplied from the said two sources, and thereafter supplying air thereto to form a proportioned emulsion which will be conducted to a further air supply by which the emulsion is diluted to the proper 25 extent to form an explosive mixture and then sucked to the engine.

In the preferred form of my invention the liquid fuel flowing from the constant level reservoir is divided into two streams, one 30 stream flowing to a well communicating with the atmosphere, and the other flowing directly to a nozzle subject to suction. These two streams, one of which will deliver an approximately constant volume per unit of 35 time, while the other will vary according to suction, are joined together in a suitable channel and thereafter a relatively small amount of air is supplied to the combined amounts of liquid fuel to form an emulsion. 40 The conduit in which this emulsion is formed leads into a main air supply channel subject to the suction of the engine and preferably being of Venturi form, provided with the usual throttle.

45 This apparatus gives the advantage over that of my previous patent, that the liquid fuel is not vaporized at the time the emulsion is formed, and consequently the heat lost by vaporization does not occur until the 50 emulsion enters the main air conduit, which naturally is nearer the engine than it would be in my previous patent apparatus. There is also less liability of the liquid fuel overflowing and spilling than in my previous 55 apparatus.

In the drawings, Figure 1 is a diagrammatic sectional elevation showing one form of my invention.

Fig. 2 is a similar view showing a modified form of the connection between the 60 emulsion tube and the Venturi or main air passage, and Fig. 3 is a view similar to a portion of Fig. 1 showing a modified form.

In the form of Fig. 1, *b* is the constant level reservoir from which the fuel flows to 65 the main nozzle *a* in the ordinary manner. Liquid fuel also flows from this constant level reservoir to the calibrated orifice *c* and enters the well *d*, the upper part of which communicates with the atmosphere. From 70 the well *d* the liquid fuel flows into the annular space *f* between the nozzle tube *a* and the lower part of the conduit *g*. The conduit *g* leads into the main air conduit *h*, and preferably into the Venturi portion 75 thereof, beyond which is shown the usual throttle *i*.

Small holes *r* are formed in the conduit *g* slightly above the level of the nozzle *a* as shown in Fig. 3, or approximately level with 80 the nozzle *a*, as shown in Fig. 1 to supply air to the mingled liquid fuel between the top of the nozzle *a* and the level of these air holes. Of course it will be understood that some air will pass down through the well *d* 85 and with the liquid fuel passing therefrom into the annular space around tube *a*, as is well known in the operation of my patent type of carbureter.

In the operation of the apparatus the position of the throttle *i* controls the amount of mixture drawn to the engine under the engine suction. The two streams, one issuing from the nozzle *a* and subject to the suction of the motor through conduit *g*, and 90 the other issuing through aperture *c* supplying approximately constant amount per unit of time, give correct proportion of fuel to air under different speeds and load. Of course, this constancy in the supply of fuel 95 is only obtained after the well *d* is emptied, as is well known in the art, and as explained in my Patent No. 907,953, of December 29, 1908, page 1, line 73.

This system gives approximately the same 105 compensating effect as in my previous patent, and the additional advantage that pre-heating is not as important on account of the mechanical emulsifying previous to entrance into the main mixing chamber, which 110

may be placed adjacent to the engine where the mixture will receive some heat.

In Fig. 2 I show a form similar to that of Fig. 1, except that the conduit *g* enters the venturi at an angle instead of axially, as in Fig. 1.

Variations in the form and arrangement of the parts may be made without departing from my invention, as defined in the claims.

10. I claim:

1. In a carbureter, an air conduit, and a fuel conduit discharging thereinto, said fuel conduit being provided with two sources of fuel supply, one providing a supply variable per unit of time, and one constant per unit of time.

2. In a carbureter, an emulsifying conduit leading to a mixing chamber having a throttle, a constant level chamber having two liquid fuel feeds leading into the emulsifying conduit, and means for admitting air to the mingled streams in said emulsifying conduit beyond the point where the said streams are mixed.

25. 3. In a carbureter, an emulsifying conduit having two connections with a constant level reservoir to receive liquid fuel therefrom, the two liquid supplies being arranged to mix in the emulsifying conduit, said conduit having means for supplying air to the mixed streams, a throttle and a channel to which the emulsifying conduit leads having a diluting air inlet of fixed area to form a secondary mixing chamber between the emulsifying channel and the throttle.

4. In a carbureter, an air conduit, a fuel conduit subject to the influence of air passing through the air conduit, a suction controlled fuel feed, and another fuel feed giving a fuel supply increasing at a less rate than the air supply.

45. 5. In a carbureter, an air conduit, a fuel conduit subject to the influence of air passing through the air conduit, a suction controlled fuel feed and a fuel feed giving a constant supply per unit of time both said feeds discharging into said fuel conduit.

60. 6. In a carbureter, an emulsifying conduit, a suction controlled fuel feed, and another fuel feed giving a fuel supply increasing at a less rate than the air supply, both of said feeds leading into the emulsifying conduit, said emulsifying conduit having an air inlet between the suction controlled fuel feed inlet and the engine.

65. 7. In a carbureter, an emulsifying conduit, an air conduit into which the emulsifying conduit discharges, a suction controlled fuel feed, and another fuel feed giving a fuel supply increasing at a less rate than the air supply both discharging into the emulsifying conduit, said emulsifying conduit having an air inlet between the suction controlled fuel feed inlet and the air conduit.

8. In a carbureter, an air conduit, a fuel conduit subject to the influence of air passing through the air conduit and adapted to deliver fuel into the air conduit at an angle to the direction of the flow of air therethrough, a suction controlled fuel feed, and a fuel feed supply constant per unit of time both discharging into the fuel conduit.

9. In a carbureter, an emulsion conduit, an air conduit into which said emulsion conduit discharges, a suction controlled fuel feed, and a fuel feed constant per unit of time both discharging into the emulsion conduit, said emulsion conduit having an air inlet between the suction controlled fuel feed inlet and the air conduit.

10. In a carbureter, an air conduit, a fuel conduit subject to the influence of air passing through the air conduit, a suction controlled fuel feed, and a fuel feed adapted to deliver a constant supply per unit of time, both said feeds discharging into the fuel conduit, and a constant level supply chamber for said feed.

11. In a carbureter, the combination of a constant level chamber, a nozzle receiving liquid fuel therefrom and extending above the fuel level in said chamber, a choke tube, a pipe surrounding said nozzle and having its outlet in the choke tube spaced apart from the orifice of said nozzle, and means for supplying fuel to said pipe independently of the nozzle, the pipe having air inlets arranged to emulsify the mingled streams of fuel in said pipe, and means for supplying air to said choke tube to mix with said emulsion.

12. In a carbureter, the combination of a choke tube, a nozzle, means for supplying fuel to said nozzle, an emulsion pipe surrounding said nozzle, said pipe extending in the same direction as the nozzle and having its outlet in said choke tube distant from the orifice of said nozzle, means for supplying fuel to said pipe independently of said nozzle, and means for supplying air to said choke tube adjacent to the outlet of said pipe.

13. In a carbureter, the combination of a choke tube, a nozzle, means for supplying fuel to said nozzle, a pipe surrounding said nozzle and having its outlet in said choke tube distant from said nozzle, a well in communication with the atmosphere and in communication with said pipe independently of the nozzle, and means for supplying fuel to said well independently of said nozzle.

14. In a carbureter, the combination of a choke tube, a nozzle, means for supplying fuel to said nozzle, a pipe surrounding said nozzle and having an outlet in the choke tube distant from the nozzle outlet, a well in communication with the atmosphere and in communication with said pipe exteriorly of and independent of the nozzle, and means

for supplying fuel to said well independently of said nozzle.

15. In a carbureter, an air conduit, a second conduit leading thereto, means for supplying auxiliary air to said second conduit, said second conduit being subject to the influence of air passing to said conduit, a suction-controlled fuel feed, and a fuel feed adapted to give a constant supply per unit of time,

both of said feeds discharging into the second conduit; substantially as described.

In witness whereof I have signed this specification in the presence of two witnesses.

FRANÇOIS BAVEREY.
